(57) **CLAIM**

The ornamental design for a brush for cosmetic use, as shown and described.

DESCRIPTION

FIG. 1 is a top view of the claimed design. The side view and bottom view are the same as FIG. 1, as the design is symmetric along its longitudinal axis.

FIG. 2 is a front view of the claimed design; and,
FIG. 3 is an isometric view of the claimed design.

The dash-dot-dash line represents the bounds of the claim and forms no part thereof. The portion of the head and the stem of the brush presented in broken lines form no part of the claimed design.
